UNITED STATES PATENT OFFICE.

DIBRELL L. DU VAL, OF LITTLE ROCK, ARKANSAS.

COMBINED TRACE-EYE PROTECTOR AND SPACING-STRIP.

1,082,473.

Specification of Letters Patent. Patented July 16, 1912.

Application filed November 25, 1911. Serial No. 662,408.

To all whom it may concern:

Be it known that I, DIBRELL L. DU VAL, a citizen of the United States of America, residing at Little Rock, in the county of 5 Pulaski and State of Arkansas, have invented new and useful Improvements in Combined Trace-Eye Protectors and Spacing-Strips, of which the following is a specification.

10 This invention relates to improvements in a combined trace eye protector and spacing strip.

One object of the present invention is the provision of a combined trace eye protector 15 and spacing strip which shall be so constructed as to protect the eye of the trace in the application of the same to a swingletree, and at the same time prevent lateral movement of the trace on the swingletree 20 thereby reducing the wear on the parts to a minimum.

Another object of the invention is to provide a device of this character which shall include a strip of flat material twisted upon 25 itself to provide an eye protector for the eye of the trace and at the same time form a spacing strip whereby the trace may be rigidly secured to the swingletree.

With the above and other objects in view 30 which shall appear as the description progresses, the invention consists in the construction, combination and arrangement of parts hereinafter described and particularly pointed out in the appended claims.

35 In the drawings forming a part of this specification; Figure 1 is a perspective view of a swingletree, showing traces attached thereto and embodying the present invention, the traces being partly broken away. 40 Fig. 2 is a longitudinal sectional view through a trace embodying the present invention, and Fig. 3 is a detail perspective view of a combined eye protector and spacing strip, constructed in accordance with the 45 present invention.

Referring more particularly to the accompanying drawings, in which like numerals of reference designate similar parts throughout the several views, 1 designates the swingletree provided at its opposite ends with

the usual buttons or hooks 2, designed to receive the traces 3 through the medium of the eyes 4 of the latter.

The combined trace eye protector and spacing strip is designated in general at A, 55 and as shown comprises a flat strip 5 constructed of leather, metal or any other suitable or preferred material. Intermediate its ends the strip 5 is bent upon itself as at 6 to provide a loop 7, adapted to aline with the 60 eye 4 of the trace 3. The opposite ends of the loop forming portion of the strip are twisted upon themselves as at 8 and terminate in superimposed securing members 9 arranged in a plane at right angles to the 65 plane of the loop forming portion of the strip and designed to receive rivets 10, or other suitable fastening devices whereby the securing members 9 may be fastened to the 70 trace 3 adjacent the eye 4 thereof.

In the application of the trace to the swingletree, the button or hook 2 of the former is inserted through the loop 7 of the device A, after which the said hook is projected through the eye 4 of the trace. Lat- 75 eral movement of the trace upon the swingletree is prevented owing to the loop forming portion of the strip 1 being arranged in a plane at right angles to the plane of the securing members 9, thereby causing the 80 free edges of the loop 3 to engage the outer end of the swingletree adjacent the hook 2 thereon.

From the above description taken in connection with the accompanying drawings, it 85 will be seen that I have provided a combined trace eye protector and spacing strip which serves to protect the eye of the trace against tearing and mutilation, incident to the action of the trace on the swingletree, 90 and at the same time holds the trace upon the swingletree in such a manner as to prevent the lateral movement of the trace relatively to the swingletree whereby the wear on the parts is reduced to a minimum. 95

Having thus described my invention what I claim and desire to secure by Letters Patent is:

1. The combination with a trace, of a combined trace eye protector and spacing 100

strip comprising a strip of flat material twisted upon itself and secured to the trace adjacent the eye thereof to prevent lateral movement of the trace upon a swingletree and the mutilation of the eye of the trace.

2. The combination with a trace, of a trace eye protector comprising a strip of flat material twisted upon itself and forming a spacing strip and located adjacent the

eye of the trace to prevent lateral movement 10 of the trace upon a swingletree.

In testimony whereof I affix my signature in presence of two witnesses.

DIBRELL L. DU VAL.

Witnesses:

W. H. SUTTON,
W. B. KENNEDY.
